R. E. ACRE.
INTERNAL COMBUSTION ENGINE.
FILED MAR. 4, 1920.

Inventor
Ray F. Acre
William, Brasbury ^{See} ~~Attys.~~

UNITED STATES PATENT OFFICE.

RAY E. ACRE, OF WHEATON, ILLINOIS, ASSIGNOR TO UNIVERSAL ENGINEERING COMPANY, OF MAYWOOD, ILLINOIS, A CORPORATION OF ILLINOIS.

INTERNAL-COMBUSTION ENGINE.

Application filed March 4, 1920. Serial No. 363,147.

To all whom it may concern:

Be it known that I, RAY E. ACRE, a citizen of the United States, residing at Wheaton, in the county of DuPage and 5 State of Illinois, have invented certain new and useful Improvements in Internal-Combustion Engines, of which the following is a full, clear, concise, and exact description, reference being had to the accompanying 10 drawings, forming a part of this specification.

My invention relates to internal combustion engines and particularly to the construction of the cylinder and crank case, by 15 means of which several advantages are derived. My invention is particularly applicable to engines of the two cycle type. It comprises forming the crank case with a cylindrically shaped extension containing the 20 intake and exhaust passages, forming the cylinder so as to extend downwardly into this cylindrical portion of the crank case and providing ports through the cylinder, registering with the passageways in the cylindrical portion of the crank case.

By the foregoing construction I am able accurately to machine both the inside and outside of the lower portion of the cylinder casting so that the metal will be of uniform 30 thickness, and free from unsymmetrical projections, whereby distortion in expansion is obviated. A further result of this construction is that the exhaust pipe may be permanently attached to the crank case casting, 35 thus permitting the cylinder to be removed for the removal of carbon without the necessity of disconnecting the exhaust pipe. Another object of this construction is that the intake and exhaust ports through the cylinder wall may be machined from the outside, 40 thus providing an easier and more accurate method of location and machining than when the operation is performed from within. Another advantage in this construction resides in the fact that the intake port may be cast as a mere bulge in the crank case housing, and therefore does not require a separate core, with the consequential loss of castings through core slippage, breakage and the like. 45 Another advantage arising from the use of my invention is that the heat imparted to the metal through the exhaust gases is prevented from overheating one side of the cylinder proper, by the fact that the exhaust

passage is in a casting separated by a slight 55 gap from the cylinder casting, thus minimizing distortion of the cylinder through variations in local temperatures.

My invention is illustrated in the accompanying drawing in which—

Figure 1 is a section through the cylinder and a portion of the crank case;

Figure 2 is a section taken on the line 2—2 of Figure 1; and

Figure 3 is a section taken on the line 3—3 65 of Figure 1.

Referring to the drawing, the crank case is provided with an upwardly extending portion 4, cast integrally with the crank case and machined cylindrically, to receive the 70 skirt of the cylinder 5. The upper portion of the cylinder 5 is provided with cooling fins 6 and with a flange 7 adapted to be clamped upon the co-acting flange 8 of the crank case extension 4, by means of two bolts, 75 one of which is shown in dotted lines at 9. A lead or copper packing washer 10 is preferably clamped between the flanges of the cylinder and crank case extension to prevent leakage. The skirt portion 5 of the cylinder is preferably machined both inside and 80 outside, so that it may be made of uniform thickness, thus preventing warping such as occurs in a heated cylindrical body having walls of varying thickness. Intake ports 12 and an 85 exhaust port 13 are machined through the skirt of the cylinder, so as to register with the intake passage 14 and exhaust passage 15 respectively. The intake passage 14 is not, as is customary, cast as a tubular portion 90 of the cylinder, but may be cast merely as a bulge upon the cylindrical portion of the crank case extension.

The interiors of the cylinders of internal combustion engines become coated with carbon in use, and it occasionally becomes necessary to remove the cylinders for the purpose of removing this coating of carbon. By my construction the cylinder may be entirely removed without disturbing the 100 connection of the exhaust pipe, which ordinarily must be removed when cylinders of the type heretofore in use are removed from the crank case.

Although my invention is illustrated as 105 embodied in a specific structure, it may be applied to other structures without departing from the spirit or scope of my invention.

What I claim is:

1. In an internal combustion engine, a crank casing having a projection thereon containing intake and exhaust passages, a cylinder adapted to fit within said projection and having a skirt forming one wall of the intake passage and having ports registering with the upper part of the intake passage and with the exhaust passage. 35
- 10 2. In an internal combustion engine, the combination with a crank case housing having a cylindrical cylinder supporting extension, a cylinder carried by said extension having a skirt projecting within the 40 crank case extension, the crank case extension being internally bored to fit closely about the external cylindrical surface of the cylinder skirt, said crank case extension having a bulged portion providing an intake passage, said skirt having an opening 45 registering with the upper portion of said intake passage.
- 15 3. In an internal combustion engine, the combination with a cylinder having intake and exhaust ports in position to be uncovered at the end of the out stroke of the piston, a flange around the outside of said cylinder, located above the line of said ports, a portion of said cylinder extending below 50 said ports, a crank case having a flange

registering with the flange of said cylinder, and having an intake passage with which the intake port of said cylinder registers, and having an exhaust passage with which the exhaust port of said cylinder registers, and means to clamp the flange of said cylinder onto the flange of said crank case. 35

4. In an internal combustion engine, a cylinder having intake and exhaust ports, a crank casing, the crank casing having an integral cylinder supporting extension into which the cylinder projects, the crank casing extension having intake and exhaust passages formed therein, which register with the intake and exhaust ports respectively. 40

5. In an internal combustion engine, a cylinder having an intake port, a crank casing having an integral cylinder supporting extension adapted to receive the cylinder, the extension having a bulged portion providing an intake passage opening directly into the intake port. 50

In witness whereof, I hereunto subscribe my name this 2nd day of March, 1920.

RAY E. ACRE.
